(57) **CLAIM**

The ornamental design for an ink cartridge, as shown and described.

DESCRIPTION

FIG. 1 is a perspective view of an ink cartridge;

FIG. 2 is a right side view thereof; and,

FIG. 3 is an enlarged partial cross-sectional view thereof taken along the lines 3—3 of FIG. 2 and between the arrows A—A of FIG. 2.

The broken lines are for illustrative purposes only and form no part of the claimed design.
